MASSAGER

Martell J. Kaliski, Oakland, Calif.

Application March 4, 1957, Serial No. 45,098

Term of patent 14 years

(Cl. D83—1)

FIG. 1.

FIG. 4.

FIG. 2.

FIG. 3.

Fig. 1 is a perspective view of a massager showing my new design;

Fig. 2 is a top plan view of Fig. 1;

Fig. 3 is a bottom plan view of Fig. 1; and

Fig. 4 is a left side elevational view of Fig. 2.

I claim:

The ornamental design for a massager, substantially as shown.
